SIDE FRAME

Application filed August 6, 1928. Serial No. 297,820.

REISSUED

This invention relates to side frames for railway car trucks and in particular to cast side frames incorporating integrally formed journal boxes.

5 In building frames of this type for certain classes of railway service, the requirements of definite rigidity and minimum of deflection under maximum imposed loads, in the face of a definite weight limitation of casting, 10 create difficult problems for the designer. Metal must be distributed where it is most efficacious and care must be exerted to insure internal fibre stresses remaining within reasonable bounds.

15 An object of the present invention is to produce a side frame of the above mentioned type combining maximum rigidity and stiffness, within a definite weight and fiber stress limitation; through a proper positioning of 20 members and a correct distribution of metal.

Another object is to produce a side frame of a design to successfully fulfill all requirements of manufacture, test and service, and one which performs these and other functions 25 without additional weight in the frame.

With these and various other objects in view, the invention may consist of certain novel features of construction and operation as will be more fully described and particularly pointed out in the specification, drawings and claims appended hereto.

In the drawings, which illustrate an embodiment of the device and wherein like reference characters are used to designate like 35 parts—

Figure 1 is a longitudinal side elevation of substantially one half of a side frame which is the subject matter of this invention;

Figure 2 is a top plan view of the side 40 frame illustrated in Figure 1;

Figure 3 is a graphic representation of concurrent forces acting in the frame under service conditions;

Figure 4 is an enlarged sectional elevation 45 through the tension member of the frame, the same being taken substantially in the plane as indicated by the line 4—4 of Figure 1;

Figure 5 is an enlarged sectional elevation through the tension member of the frame, 50 the same being taken substantially in the

plane as indicated by the line 5—5 of Figure 1;

Figure 6 is an enlarged sectional elevation through the journal box and frame member, the same being taken substantially in the 55 plane as indicated by the line 6—6 of Figure 1;

Figure 7 is an enlarged sectional elevation through the compression member of the frame, the same being taken substantially in 60 the plane as indicated by the line 7—7 of Figure 1; and

Figure 8 is an enlarged sectional elevation through the compression member of the frame, the same being taken substantially in 65 the plane as indicated by the line 8—8 of Figure 1.

Referring more particularly to Figures 1 and 2, it will be seen that the integrally cast side frame consists substantially of an upper 70 compression member 20; a lower tension member 21, the vertical struts or pedestals 22—22, journal boxes 23—23 and the portions 24—24 overlying and adjacent to said journal boxes formed by the merging of the 75 compression and tension members 20 and 21, respectively.

The compression member 20 is of multiple section, varying from a substantially rectangular section in the merged portion above 80 the journal boxes, as illustrated in Figure 6, to an open channel section illustrated in Figure 7 and to a rectangular closed section on the frame center as illustrated in Figure 8. The tension member 21 is of similar variation in sectional form, as represented in Figures 4 and 5, in which Figure 4 is of reinforced closed rectangular construction and Figure 5 is of open channel section.

While the general type of side frames 90 shown is not uncommon in the art, with the constant increase in car loadings difficulty has been experienced in securing the requisite rigidity without exceeding the imposed limitations of casting weight. To obviate this it 95 was necessary to determine the sections of maximum stress, and after a series of experiments and with the use of strain gauges under varied loads, and after mathematical and graphic analyses, it was found that the maxi- 100

mum deflection occurred in the regions adjacent the journal boxes and in proximity to the point of mergence of the compression member 20 and the tension member 21.

5 In the present perfected invention the requisite stiffness and rigidity has been secured without materially adding to the total weight by internally increasing the thickness of the side walls 25-25 of region 24 to the 10 left of the dotted boundary indicating line 26, over the thickness of the side walls of the members 20 and 21 and extending to the right of corresponding line 27, all as viewed in Figure 1. Between said limiting 15 lines 26 and 27 there is a gradual transition of wall section. A similar effect may be had by increasing the thickness of the walls radially from a point defined by the junction of the line AB and the extreme inner corner of the journal box, i. e., at point 62, the large 20 radius of the thickened section being the distance from the point 62 to the line 27 measured along line AB, i. e., from 62 to 64.

An understanding of the forces involved 25 may be had by reference to Figure 3. This figure diagrammatically represents the above side frame carrying a vertical load, the resultants thereof each being substantially one half of the total load and one of which is 30 indicated by the force "W" acting through the journal box center. Considered as a truss, we have a force of compression F_1 in the top member and a tensile force F_2 in the lower member. The horizontal components 35 of these forces must balance each other to satisfy the necessary condition of equilibrium, therefore: $F_1 \cos a = F_2 \cos b$.

The section AB is therefore subject to a 40 shearing force $F_1 \cos a$ and it should be observed that this section passes through approximately the center of the section indicated by the line CD. Section CD is at the same time subject to a vertical shear equal 45 to the journal box load "W" and this shear is carried almost entirely by the side walls, so it may be said that each side wall carries a total shear of $\frac{1}{2}W$. It is well known that when a rectangular section is subject to a shearing force, the maximum shearing 50 stress occurs at the center of the section, and equals one and one half times the average shearing stress.

Thus, the metal in the region under consideration is subjected to the combined horizontal shear and a maximum vertical shear. 55 The combined shearing stress is therefore abnormally high and the result is a high tensile stress as represented by force "R" which acts in a direction of approximately 45 degrees to the horizontal and bisects the angle between the section lines AB and CD, and since the point E, at the journal box and junction of the line of force of F_2 and section AB, is at a reentrant angle it will carry a 60 high stress due to concentration. To take 65

care of this high resultant force without excessive fiber stresses the walls of the region 24 were thickened as before-mentioned, it not being so essential that the tension and compression members be thickened as the shearing stresses in them are relatively unimportant. In order to further reinforce the region adjacent the inner corner of the journal box, diagonal ribs 34 and 36 are provided, 70 said ribs extending along the tension member, i. e., closely adjacent and in the same direction as the resultant of the stresses, and merging into the tension member at points 58 and 60 adjacent the section thickness defining line 27.

75 It is to be understood that I do not wish to be limited by the exact embodiment of the device shown, which is merely by way of illustration and not limitation, as various and other forms of the device will of course be 80 apparent to those skilled in the art without departing from the spirit of the invention or the scope of the claims.

I claim:

1. A truck side frame having an upper compression member and a lower tension member merging at the ends thereof to form integral journal boxes and having a region overlying 90 said journal boxes, and a reinforcing member disposed intermediate the upper and lower 95 portion and along one of said members, and extending substantially in the same direction thereof.

2. A cast side frame for railway car trucks having an upper compression member and a lower tension member, said members being 100 of varied section and merging at journal boxes integral therewith, a portion of the walls of said members overlying and adjacent to said journal boxes being thicker than 105 the walls of said compression and said tension members.

3. In an integrally cast frame for railway car trucks, the combination of an upper compression member, lower tension member, journal boxes connected thereto, and a section 110 overlying said journal boxes formed by the merging of the aforesaid compression and tension members at their outer ends, the side walls of said overlying section adjacent to 115 said journal boxes being of greater thickness than the side walls of said compression and tension members prior to the points of mergence.

4. In an integrally cast side frame for railway car trucks, the combination of journal boxes, a compression member of substantially rectangular and channel cross section, having 120 end portions of substantially rectangular cross section extending over said boxes, and 125 a tension member of substantially rectangular and channel cross section merging with said journal boxes and said compression member, the side walls of the combined tension and compression members and of the resultant 130

- end portions thereof being of thicker wall section than that of the side walls of said compression and tension members prior to their emergence into a composite structure.
5. A side frame for railway trucks comprising in a single casting multiple section side members, journal boxes and portions overlying and adjacent to said journal boxes, the side walls of said overlying portions being of thicker section than the side walls of said side members.
6. In a structure of the character described, the combination of component side members having a region formed by the junction of said component members, the side walls of said region being of thicker section than the side walls of either of said members.
7. In a structure of the character described, the combination of multiple cross section compression and tension members having pedestals forming a substantially square center portion and two triangular end portions, journal boxes formed integrally with said tension and compression members at the outward apex of said triangular sections, said members having a region overlying and adjacent to said journal boxes, the side walls of said region being increased in thickness internally over the side wall section of said tension and said compression members.
8. In a side frame, the combination of upper and lower chord members, journal boxes connected thereto, said chords having sections of the walls thereof of varying thicknesses adjacent said journal boxes.
9. In a side frame, the combination of upper and lower chord members, journal boxes connected thereto, said chords having sections of the walls thereof of increased thicknesses adjacent said journal boxes.
10. In a truck side frame, the combination of an upper compression member, a lower tension member, a journal box integrally formed therewith and a section overlying said journal box formed by the merging of said members adjacent the ends thereof, said section having side walls, said side walls being of increased thickness adjacent the journal box.
11. In a truck side frame, the combination of an upper compression member, a lower tension member, a journal box integrally formed therewith and a section overlying said journal box formed by the merging of said members adjacent the ends thereof, said section having side walls, said side walls being of increased thickness adjacent the journal box, and a brace member extending from said journal box along one of said members and merging therewith.
12. In a truck side frame, the combination of an upper compression member, a lower tension member, a journal box integrally formed therewith and a section overlying said journal box formed by the merging of
- said members adjacent the ends thereof, said section having side walls, said side walls being of increased thickness adjacent the journal box, and a brace member extending along said tension member and merging therewith.
13. In a truck side frame, the combination of an upper compression member, a lower tension member, a journal box integrally formed therewith and a section overlying said journal box formed by the merging of said members adjacent the ends thereof, said section having side walls, said side walls being of increased thickness adjacent the journal box, and a diagonal brace member extending from a corner of said journal box and along said tension member and merging therewith.
14. In a truck side frame, the combination of an upper compression member, a lower tension member, a journal box integrally formed therewith and a section overlying said journal box formed by the merging of said members adjacent the ends thereof, said section having side walls, said side walls being of increased thickness adjacent the journal box, and a diagonal brace member extending from the inner corner of said journal box and along said tension member and merging therewith.
15. In a truck side frame, the combination of an upper compression member, a lower tension member, a journal box integrally formed therewith and a section overlying said journal box formed by the merging of said members adjacent the ends thereof, said section having side walls, said side walls being of increased thickness adjacent the journal box, and a diagonal brace member extending from a corner of said journal box and along said tension member and merging therewith.
16. In a truck side frame, the combination of an upper compression member, a lower tension member, a journal box integrally formed therewith, and a section overlying said journal box formed by the merging of said members adjacent the ends thereof, said section having side walls, said side walls being of increased thickness adjacent the journal box, and a diagonal brace member extending from the inner corner of said journal box and along said tension member and merging therewith, said brace member being spaced from the upper and lower portions of said tension member.
17. In a truck side frame, the combination of an upper compression member, a lower tension member having a web portion, a journal box integrally formed with said members and disposed so that the said web portion merges into said journal box below the corner thereof, a section of the junction of said tension

and compression members being of substantially box section having side walls of increased thickness from the thickness of the walls of the tension and compression members.

18. In a truck side frame, the combination of an upper compression member, a lower tension member having a web portion, a journal box integrally formed with said members and disposed so that the said web portion merges into said journal box below the corner thereof, a section of the junction of said tension and compression members being of substantially box section having side walls of increased thickness from the thickness of the walls of the tension and compression members, and a brace member extending from said journal box and merging into said side walls.

19. In a truck side frame, the combination of an upper compression member, a lower tension member having a web portion, a journal box integrally formed with said members and disposed so that the said web portion merges into said journal box below the corner thereof, a section of the junction of said tension and compression members being of substantially box section having side walls of increased thickness from the thickness of the walls of the tension and compression members, and a brace member extending from said journal box and merging into said side walls, said brace member extending substantially in the direction of said tension member.

20. In a truck side frame, the combination of an upper compression member, a lower tension member having a web portion, a journal box integrally formed with said members and disposed so that the said web portion merges into said journal box below the corner thereof, a section of the junction of said tension and compression members being of substantially box section having side walls of increased thickness from the thickness of the walls of the tension and compression members, and a brace member extending from said journal box and merging into said side walls, said brace member extending in the direction of said tension member and being intermediate the top and bottom of said member.

21. In a truck side frame, the combination of an upper compression member, a lower tension member, a journal box integrally formed therewith and a section overlying said journal box formed by the merging of said members adjacent the ends thereof, said section having side walls, said side walls being of increased thickness radially from the inner extreme corner of said journal box.

22. In a truck side frame, the combination of an upper compression member, a lower tension member, a journal box integrally formed therewith and a section overlying said journal box formed by the merging of said members adjacent the ends thereof, said section having side walls, said side walls be-

ing of increased thickness radially from the inner extreme corner of said journal box, and a brace member extending from said corner of said journal box and merging into the walls of said section.

23. In a truck side frame, the combination of an upper compression member, a lower tension member, a journal box integrally formed therewith and a section overlying said journal box formed by the merging of said members adjacent the ends thereof, said section having side walls, said side walls being of increased thickness radially from the inner extreme corner of said journal box, and a brace member extending diagonally from said corner of said journal box in the direction of said tension member.

24. In a truck side frame, the combination of an upper compression member, a lower tension member, a journal box integrally formed therewith and a section overlying said journal box formed by the merging of said members adjacent the ends thereof, said section having side walls, said side walls being of increased thickness radially from the inner extreme corner of said journal box, and a brace member extending diagonally from said corner of said journal box in the direction of said tension member, and spaced from the upper and lower portions of said tension member.

25. In a truck side frame, the combination of an upper compression member, a lower tension member, a journal box integrally formed therewith and a section overlying said journal box formed by the merging of said members adjacent the ends thereof, and a brace member extending from said journal box directionally along one of said members and integral therewith.

26. In a truck side frame, the combination of an upper compression member, a lower tension member, a journal box integrally formed therewith and a section overlying said journal box formed by the merging of said members adjacent the ends thereof, and a brace member extending from said journal box along said tension member and merging therewith.

27. In a truck side frame, the combination of an upper compression member, a lower tension member, a journal box integrally formed therewith and a section overlying said journal box formed by the merging of said members adjacent the ends thereof, and a diagonal brace member extending from a corner of said journal box and along said tension member and integral therewith, said brace member being spaced from the upper and lower portions of said tension member.

Signed at Chicago, Illinois, this 2nd day of August, 1928.

GEORGE G. FLOYD.
